UNITED STATES PATENT OFFICE.

EUGEN RITTER, OF EHRENFELD, GERMANY.

SCREW-FASTENING FOR BOXES OR CASES.

SPECIFICATION forming part of Letters Patent No. 321,054, dated June 30, 1885.

Application filed February 28, 1885. (No model) Patented in Germany February 26, 1884, No. 28,254, and in England April 8, 1884, No. 5,554,

To all whom it may concern:

Be it known that I EUGEN RITTER, of Ehr-
enfeld, Germany, have invented an Improve-
ment in a Screw-Fastening for Boxes or Cases;
5 and I hereby declare the following to be a full,
clear, and exact description of the same.

My invention relates to an improved means
for closing and securing boxes, for which Pat-
ents have been granted me in foreign countries,
10 as follows: Germany, No. 28,254, February 26,
1884, and England, acceptance No. 5,554,
April 8, 1884.

My invention consists of a screw which
passes through the cover or part to be secured,
15 and a cylindrical nut having internal screw-
threads, into which the screws fits and external
threads by which it may be screwed into the
edge or body of the box, so as to form per-
manent sockets into which the screws may be
20 inserted at any time, and from which they
may be removed when it is desired to remove
the cover without defacing or breaking the
wood-work.

Referring to the accompanying drawings for
25 a more complete explanation of my invention,
Figure 1 is a side elevation showing a box
and a cover having my invention applied to
them. Fig. 2 is a plan view of the box, show-
ing the sockets fixed in its edges. Fig. 3 is a
30 view of a tool by which the sockets may be
introduced and seated.

In the usual method of securing the covers
of boxes or cases in which nails or ordinary
wood screws are used, the holes soon become
35 broken, so that the screw-threads will no longer
hold. My invention is especially useful for
boxes or cases in which cartridges or other
articles are to be transported, and which are
40 intended to be used frequently and for a con-
siderable length of time.

A is a screw by which the cover of the box
or case is to be secured. It may have a coni-
cal head, a, with the usual slot, b, for the use
45 of the screw-driver, the point or opposite end
being threaded, as shown at g.

B is a hollow cylindrical nut, the interior
of which may be screw-threaded for a part or
the whole of its length, as shown, these threads
being of such a pitch as to receive the threads
50 of the screw A.

Upon the exterior of the cylindrical nut B

are formed coarse screw-threads C, which are
intended to hold the cylinder in place in the
edges of the body of the box D. This cylind-
rical nut may be inserted by means of a 55
wrench, which, as is shown at E, Fig. 3, has trans-
verse or T-shaped handles and screws-threads
at its opposite ends, which threads fit the in-
terior of the nut, so that they may be turned
into it until the shoulder at the upper end of 60
the threads rests upon the top of the nut.

By turning the whole device around the nut
may be screwed into a hole previously made
for it until the upper end is flush with the
edge of the box into which it is inserted. This 65
upper end may preferably have a beveled
flange, so that it fits snugly into the hole and
makes a good finish at the top.

A groove or channel may be made trans-
versely across the exterior of one side of this
cylindrical nut; or it may pass into it a short
distance, so as to receive a pin, F, which may
be driven in it after the nut has been screwed
70 down to its place. This pin will then hold it,
so that it will not come out when the screw is
removed.

As many of these cylindrical nuts may be
fixed in the edge of the box as may be neces-
sary for the purpose of securing the cover H,
80 which has corresponding holes bored through
it for the reception of the screws A.

By this construction I provide a permanent
method of securing the parts of boxes or cases
together, and they may be easily separated
without destroying the wood-work.

Having thus described my invention, what
I claim as new, and desire to secure by Letters
85 Patent, is—

A screw having threads at one end and a
head at the opposite end, in combination
with a cylindrical nut or socket having its in-
terior threaded to receive and hold the screw,
and its exterior threaded so that it may be
screwed into the edges of the box or case, and
having also a transverse hole or slot for the
95 introduction of a locking-pin, substantially
as herein described.

In witness whereof I have set my hand.
EUGEN RITTER.
